UNITED STATES PATENT OFFICE.

WILLIAM F. COCHRANE, OF HARPER'S FERRY, WEST VIRGINIA.

HARVESTER.

SPECIFICATION forming part of Letters Patent No. 325,319, dated September 1, 1885.

Application filed September 19, 1884. (No model.)

To all whom it may concern:

Be it known that I, WILLIAM F. COCHRANE, of Harper's Ferry, in the county of Jefferson and State of West Virginia, have invented 5 certain new and useful Improvements in Harvesters; and I do hereby declare the following to be a full, clear, and exact description of the same, reference being had to the accompanying drawings, forming a part of this specification, and to the figures and letters of reference marked thereon.

My present invention relates to certain novel and improved means for attaching or connecting the frame carrying the platform and cutting mechanism to the main frame of a grain-binder; and it consists, generally, in certain novel details of construction, which I will first describe, and then point out particularly in the claims at the end of this specification.

20 In the accompanying drawings, which are designed to illustrate one form in which my said invention may be applied, Figure 1 is a plan view of the machine showing in dotted lines the platform in position for transportation. Fig. 2 is a rear elevation; Fig. 3, a detail of the front coupling; Figs. 4 and 5, top and side views of the brackets forming the joint at the rear of the frame.

The letter A indicates the main frame of the 30 machine, arranged and adapted to support the usual elevating-apron, B, and binding mechanism, as at C. As shown in the drawings, the main frame is itself mounted upon a single supporting and driving wheel, D, in the manner common to the one-wheel type of machines, although, as will be readily understood, my invention, as hereinafter described and claimed, may be as well applied to the two-wheel type.

The letter E indicates a suitable platform 40 carrying the cutting mechanism, as at E', and provided with a suitable carrying device, E'', for delivering the cut grain to the elevator B.

The adjustment of the cutting apparatus is effected through the medium of the tongue, 45 which latter is pivoted to the main frame, and provided with suitable devices for tilting the main frame, and thereby the cutter-bar, although other well-known mechanisms or arrangement of parts may be adopted, as preferred.

The frames and mechanisms, as thus far re-

ferred to, are the well-known forms and constructions, and further description thereof is deemed unnecessary to a complete understanding of my present improvement.

55

As distinguished from prior machines of this class as usually constructed, the frame comprising the platform, and cutting and carrying mechanism, is made complete and separate from the main frame—that is to say, the two 60 frames are so constructed and combined that they can be readily separated without disturbing the relation of their several mechanisms, and when brought into juxtaposition are in condition to at once begin operating.

65

With this end in view, and for the further and more important purpose of providing a means whereby the platform may be swung around, or to the rear of the main frame when the machine is to be transported from place 70 to place, I connect the two frames by a pivotal or swinging joint at or near their rear adjacent corners, and provide a suitable locking device forward to support and sustain the platform and cutting mechanism in position.

75

The means for accomplishing this are many and obvious, and in the drawings I have illustrated a form of joint adequate for the purpose. It consists, essentially, of the two brackets or castings, F F', the one, F, provided 80 with flanges f f, to receive the end of the rear sill, a, and the eyes a', to receive the pivot, and the other, F', provided with flanges f' f' to fit, and embrace the ends of the timbers e e of the main frame, and having the long tubular socket 85 a', the latter fitting between the eyes a' of the bracket F. The brackets F F' being applied and secured to the timbers a and e e, when the parts are brought together with the socket a' between the eyes a', they are united, and 90

the platform is firmly secured upon and jointed to the main frame by a vertical bolt, b, passed through the eyes and socket, as shown. It will be observed from an inspection of figures that the eyes and socket referred to project 95 somewhat to the rear, in order to allow the platform to swing clear around and against the rear of the main frame, and in order to give greater strength and rigidity to the joint the bolt or pin b, is extended through a sleeve, 100 b', and the bar b'', of the main frame. The two frames are connected at or near their forward

ends by a suitable separable joint or coupling, G, which latter may be composed of the two members $g\ g$, one attached to either frame, and a removable bolt or locking-pin, g' , passing 5 through eyes in the parts $g\ g$.

It will be readily understood that by virtue of the arrangement described the platform can at any time and by the simple unlocking of the forward coupling, as by the withdrawal of 10 the pin g' , be swung upon its rear pivot until it occupies a position in rear of the main frame, to which it may conveniently be attached by any suitable hook or locking device—such as a bolt and nut, T, shown in Fig. 15 1—and when in this position the machine as a whole can easily be transported from place to place or stored without the necessity of taking it to pieces.

If the machine to which my invention is applied 20 has the reel mounted upon the platform, then, of course, it will swing back with the latter; but when, as shown in the drawings, the reel is supported wholly upon the main frame, in order that it may be swung backward, I mount the reel-support upon a pivoted 25 base. Thus, as shown in the drawings, the board T', upon which the reel-supports are mounted, is pivotally secured by the bolt which forms the rear pivot of the platform, and the 30 same bolt which effects the locking of the front coupling, also secured to the front end of said board T', in position upon the front bar, t, of the main frame.

By thus locking and pivoting the two swing- 35 ing frames upon the same centers they can be moved together and be made to maintain their relative positions by dropping the locking-bolt through the board T' and into the coupling attached to the platform, after the 40 reel and platform have been swung clear of the main frame.

In practice it is desirable that the connection between the pitman and cutter should be of such a construction as will permit them to be easily separated or uncoupled. It may 45 also be found desirable, under certain circumstances, to provide means for applying a detachable caster-wheel at or near the front inner corner of the platform, when the latter is swung in rear of the main frame, to assist the grain-wheel in supporting the platform and balancing the machine.

I do not wish to be understood as limiting myself to the particular form or construction of the several couplings and joints as described, 55 inasmuch as other forms will readily suggest themselves to the skilled operator as soon as my present invention is disclosed.

I claim as my invention—

1. In a harvester, and in combination with 60 the main frame thereof, a reel, the support whereof is pivotally secured to the main frame to permit the reel to be swung to the rear of the machine, substantially as described.

2. In a harvester, and in combination with 65 the main frame thereof, a platform and reel-standard pivoted to the main frame and adapted to be swung in rear thereof, substantially as described.

3. In a harvester, such as indicated, the 70 combination of the main frame, the platform and reel support pivotally attached to the main frame upon the same axis, and the bolt for detachably securing the front end of platform and reel-support to the main frame, substantially as described. 75

WM. F. COCHRANE.
